UNITED STATES PATENT OFFICE.

HERMANN J. L. BLANKE, OF CHICAGO, ILLINOIS.

DEVICE FOR RECEIVING MEMORANDA.

SPECIFICATION forming part of Letters Patent No. 619,661, dated February 14, 1899.

Application filed June 22, 1898. Serial No. 684,198. (No model.)

To all whom it may concern:

Be it known that I, HERMANN J. L. BLANKE, a subject of the Emperor of Germany, residing at Chicago, in the county of Cook and State 5 of Illinois, have invented certain new and useful Improvements in Devices for Receiving Memoranda; and I do hereby declare the following to be a full, clear, and exact description of the invention, such as will enable others skilled in the art to which it appertains to make and use the same.

My invention relates to a novel construction in a device for receiving written notices, &c., during the absence of a doctor or other 15 business man, the object being to provide a device of this character which provides the paper and surface for writing and devices for hiding such writing from the eyes of all except the person for whom it is intended; 20 and it consists in the features of construction and combinations of parts hereinafter fully described and claimed.

In the accompanying drawings, illustrating my invention, Figure 1 is a perspective view 25 of my device. Fig. 2 is a central longitudinal section of the same. Fig. 3 is a detail sectional view of same on the line 3 3 of Fig. 2. Fig. 4 is a detail sectional view on the line 4 4 of Fig. 3. Fig. 5 is a detail sectional 30 view on the line 5 5 of Fig. 3. Fig. 6 is a sectional view similar to Fig. 5, showing the parts in different positions. Fig. 7 is a view in elevation, partly broken away, of the rear plate of the device. Fig. 8 is a detail sectional view on the line 8 8 of Fig. 2. Fig. 9 is a detail sectional view showing a locking 35 device omitted in Fig. 2. Fig. 10 is a sectional view on the line 10 10 of Fig. 9. Fig. 11 is an end elevation of the top plate of the 40 device.

Referring now to said drawings, A indicates a hollow metal plate, to which a casing B is pivoted by means of hooks 1, entering slots in the lower end of said plate A. Said plate 45 A is also provided with a lock 2, operated by a key 3 and adapted to engage a hook 4 on the upper end of said casing B to lock the same against said plate A. A button 5, having a shank 6 passing through said plate A 50 within said casing B, carries a disk 7, revolvable within said hollow portion of said plate A, said disk 7 having a dial 8, perceptible at

one point through an opening 9 in said plate A. A rod 10 is pivoted upon said shank 6 of said button 5, and at its upper end carries a 55 segmental plate 11, containing words, such as "Return at" and "At home," said plate being partially perceptible through the opening 12 in said plate A, and at its other end said rod 10 is provided with a small arm 13, passing through the segmental slot 14 in said plate A, by means of which said rod is turned on its pivot. Said casing B is provided with two parallel sides 15, provided with lugs 16, through which screws are adapted to pass to 60 secure the compound curved plate 17 thereto. Inclined recesses 18 between ribs 19 on said sides 15 serve to receive and hold the reel 20, upon which a roll 21 of paper is mounted. Said paper is passed over a roller 70 22 in the upper front portion of the machine, thence underneath the slotted top plate 23, over the roller 24, and downwardly between the rollers 25 and 26. A plate 27 is mounted below the plate 23 and is provided with downwardly-extending lugs 28 on each side, which are recessed, so as to rest pivotally upon a tube hereinafter described. The paper passes over said plate 27, which provides a smooth 75 firm upper surface to enable the paper to be 80 written upon. The shaft of the roller 26 passes through one of said sides 15 and carries a knob or button 29, by means of which it can be turned. A ratchet-wheel 30 is also mounted upon said shaft of said roller 26 and is adapted 85 to prevent said roller from being turned except in the direction to draw said paper from its reel, a pawl 31 being pivoted upon a shaft 32 and held in engagement with said ratchet-wheel by means of a spring 33 to prevent rotation 90 in the opposite direction. Said shaft 32 is rigid, being reversely threaded at its ends and serving to hold the upper ends of said sides 15 rigidly in relative position. Upon the other end of said shaft 32 a bell-crank 95 lever 34 is pivotally mounted and held frictionally against free rotation by means of the spring 35 bearing against the same. The arms 36 and 37 of said bell-crank lever 34 are of different lengths and are adapted to be 100 alternately engaged by a pin 38 on the other end of said roller 26. In the position shown in Fig. 5 said pin 38 engages the end of the arm 36, thus preventing further rotation of

the roller 26, while the arm 37 supports the plate 27. Upon applying pressure, such as the weight of the hand, upon the plate 27 the arms 37 and 36 will be depressed, as shown 5 in Fig. 6, thus releasing the pin 38 and enabling it to turn freely. Such depression of the plate 27 brings the arm 37 into the path of the pin 38, which as it revolves raises said arm 37 out of its path, and thereby raises the 10 plate 27 and at the same time brings the arm 36 again into its path. In this manner a given length of paper will be passed at every revolution of the roller 26 and undue waste be prevented. Said plate 23 is removably 15 mounted upon said casing B by means of perforated lugs 39 on the sides of said plate, which are adapted to enter sockets 40 on said sides 15. The inner walls of said sockets are perforated in alignment with said perforations in said lugs 39 when the latter are in place, so as to enable pins 41 to pass through both said perforations. Said pins 41 are telescopically mounted in a tube 42, extending 20 between said sockets 40, and are normally 25 held at the outer limits of their movement by means of the springs 43. Said pins 41 are each provided with lugs 44, moving in slots or recesses 45 in the ends of said tube and adapted to enter recesses 46 in the inner faces 30 of the inner walls of said sockets 40, and when said lugs 44 have entered said recesses 46 said pins move to the outer limits of their movements and enter the perforations in the lugs 39, thus engaging and rigidly holding 35 said lugs and said plate 23 in position. By turning said tube 42 by means of an arm 47 thereon, so that said lugs 44 leave said recesses 46, said pins 41 will be withdrawn from said perforations in the lugs 39, and 40 will thus release said plate 23. The plate 27 pivotally rests upon the said tube 42, as hereinbefore mentioned. Said plate 23 is provided on its forward end with an angular extension 48, provided with a slot 49, through 45 which a name-plate 50, secured to the rear face of said extension 48, can be seen.

My device is simple, efficient, durable, and cheap and, as will be obvious, is constructed with a view to prevent any tampering with 50 any part thereof. After an absence the owner of the device inserts his key and turns the casing B upon its pivot. He then tears off the free end of the paper, such tearing being aided by the serrated plate 51, and reads the 55 notes.

I claim as my invention—

1. In a device of the kind specified, a hollow plate, a casing pivoted thereto, means for locking said casing against said plate, a reel 60 of paper in said casing, means for passing said paper underneath a slotted plate on said casing and over a plate pivotally mounted below said slotted plate, such means including a roller adapted to be turned from the 65 outside of said casing, and devices actuated partially from said roller and partially from

said plate over which said paper passes, to limit the rotation of said roller and release the same at intervals, substantially as described.

2. In a device of the kind specified, the 7c combination with a movable plate over which paper is adapted to pass, and a roller for moving said paper, of devices for limiting the rotation of said roller at intervals, such devices comprising a pin on said roller, arms 75 actuated by said pin to raise said plate, and said plate to release said pin, substantially as described.

3. In a device of the kind specified, the combination with a roller adapted to operate 80 a reel of paper and provided with a pin, of a bell-crank lever having arms adapted alternately to be moved into and out of the path of said pin, one of said arms being so moved into its path by said pin and the other of said 85 arms by a plate over which said paper moves and which rests upon said arm, substantially as described.

4. In a device of the kind specified, the combination with a roller adapted to operate 90 a reel of paper, a pin on said roller, and a plate over which said paper moves, of a bell-crank lever having arms adapted to be alternately moved into and out of the path of said pin by the latter and by said plate, to 95 limit the movement of said roller at intervals, substantially as described.

5. In a device of the kind specified, a hollow plate, a casing pivoted thereto and open toward said plate, means for locking said 100 casing against said plate, slots in said plate above said casing, a dial in said hollow portion of said plate pivotally mounted upon the shank of a button projecting into said casing and adapted to revolve behind one of said 105 slots in said plate, a rod pivoted to said shank of said button and carrying a segmental dial at its upper end adapted to be visible behind another of said slots, and an arm on the other end of said rod adapted to pass through a 110 segmental slot in said plate and project into said casing, substantially as described.

6. In a device of the kind specified, a casing provided with a slotted top plate removably secured thereto by means of lugs on said 115 plate entering sockets in said casing, perforations in said lugs and the inner walls of said sockets, pins adapted to pass through said perforations to hold said plate, a tube in which said pins are telescopically mounted, 120 springs for holding said pins normally at the outer limits of their movement, and devices for withdrawing said pins from said perforations in said lugs by turning said tube, substantially as described.

In testimony whereof I affix my signature in presence of two witnesses.

HERMANN J. L. BLANKE.
